Patented July 31, 1917.

Inventor,
George W. Donley,
by *L. C. Hopper, Atty.*

UNITED STATES PATENT OFFICE.

GEORGE W. DONLEY, OF CLEVELAND, OHIO, ASSIGNOR TO THE DONLEY BROTHERS COMPANY, OF CLEVELAND, OHIO, A CORPORATION.

PACKAGE-RECEIVER.

1,235,123.

Specification of Letters Patent. Patented July 31, 1917.

Application filed September 11, 1916. Serial No. 119,373.

To all whom it may concern:

Be it known that I, GEORGE W. DONLEY, a citizen of the United States, and a resident of Cleveland, in the county of Cuyahoga and State of Ohio, have invented new and useful Improvements in Package-Receipters, of which the following is a specification.

This invention relates to delivery boxes set in walls for receiving bottles and packages, said boxes being accessible or locked on one side of the wall as required.

The prime object of my present invention is to produce an in-wall package, parcel and bottle receiving box or compartment having an outer door normally locking automatically, but which may be set to be readily opened once from outside the wall to place articles in the box. Further objects are to provide means for holding the outer door closed without positively locking it; and to employ the simplest and most inexpensive means for accomplishing the desired purposes without sacrificing convenience, certainty of operation and durability.

Referring to the accompanying drawing illustrating an embodiment of the invention which I now prefer,

Figures 1 and 2 are sectional elevations of receivers taken respectively on lines 1—1 and 2—2 of Fig. 3.

Fig. 3 is an elevation of the box with its inside door and frame removed, showing the inner side of the outer door and its frame.

Fig. 4 is a detailed inside view of the lock members on the outer door, and

Fig. 5 is an edge view of the same.

The reference letter *a* indicates a rectangular box-like casing, preferably of sheet metal, adapted to be closely fitted and fixedly secured in an aperture through a wall *w*. At each end the casing *a* is provided with reinforcements, preferably of angular cross-section, framed about large openings for doors, as at *b* and *c*. The inside door *i* is hinged at *j*—*j* to the frame *b* in any suitable well known manner, and is provided with a handle and latch, or catch *k* of any style desired, so that it can be readily opened and closed from inside a house or apartment.

The outside door *d* should be of heavier construction, close fitted to, overlapping and

strongly hinged as at *h*—*h* to its frame *c*, and provided with a projecting handle *e*; 55 so that it can be opened outwardly from the exterior of the wall *w*, except when locked inside. A catch *g* projects outward with a depending terminal lip from the interior face of the swinging end of the door *d*; 60 and beneath it is a lug *f* on the door, which lug has its outer lateral face inclined several degrees from perpendicular, as plainly shown in Figs. 4 and 5. The catch *g* may be formed integral with the door, but, since 65 it should be of harder metal, I prefer to rivet it to the door as at *m* against a vertical rib *n*.

A channel-shaped projection *p* is extended inward from the frame *c* adjacent to the 70 swinging end of the door *d*, and serves to support a fixed bolt *o* upon which a flat-sided gravity latch *l* is pivotally fulcrumed; as in Figs. 1 and 3. The latch *l* is normally overbalanced by the weight of its handle 75 end *q*, which is extended some distance into the box *a*, and a stop *s* is fixed to the projection *p* to limit the downward swing of the latch-handle. The upper terminal edge of the outer arm of the latch *l* is beveled off, 80 and adjacent thereto a substantially right angled notch *r* is formed in its upper edge; said terminal and notch being formed and placed so that the latch will normally trip under and positively engage the depending 85 lip of the catch *g* when the door *d* is closed. But when the latch-handle *q* is raised to the position shown in dotted lines in Fig. 1, then the outer arm of the latch is released from the catch *g*, and its lower edge engages 90 and wedges against the inclined side of the lug *f*, thus holding the door *d* closed by the frictional contact between the said latch and lug.

In the operation of the device it is apparent that the outside door *d* is normally locked positively, as in Fig. 1. When a package is expected to be delivered, the inside door *i* is opened and the latch-handle *q* raised until the outer end of the latch *l* engages 95 with sufficient friction the incline *f* to hold the door *d* closed against the weather and prowling animals. The door *i* is then closed; but the bearer of a package can readily pull the outer door *d* open by its 100 handle *e*, and deposit the package in the

box *a*. But when he closes the door *d*, the latch *l* being now freed from the incline *f*, trips under the lip of the catch *g* and thereby locks the door positively, so that it can 5 only be released by raising the latch-handle *g* from inside the apartment.

I have described and shown a box *a* having only one compartment, but it is obvious that the receiver may be partitioned to form 10 a plurality of compartments, each closed by an outside door *d* locking as shown herein. Inside doors *i* may also be fitted to each compartment if desired, but a single inside door to close all compartments will usually 15 be sufficient.

I further point out and distinctly claim as my invention—

1. An in-wall package receiver comprising a compartment having an outside door, 20 a latch adapted to engage and positively lock said door on its inside, and an inclined surface positioned to make wedging contact with said latch to hold the door closed by frictional means.

25 2. An in-wall package receiver comprising a compartment having an outside door hinged thereto, a gravity latch operatively mounted upon the inside of said compartment, a catch on said door adapted to trip and engage said latch as a positive lock, and 30

an inclined surface on said door against which the said latch may be wedged when released from said catch.

3. In a package receiver, an outer door-frame having a door hinged thereto, a catch 35 and an inclined-sided lug projecting inward from said door, and a gravity latch mounted on said frame so as to trip and positively engage said catch, said latch being adapted to be wedged against said lug when released 40 from said catch.

4. In a package receiver, an outer door-frame having a door hinged thereto, a catch and an inclined-sided lug projecting inward 45 from said door, a latch pivotally fulcrumed on the inside of said frame and provided with an overbalancing inwardly projecting handle, an outer end of said latch adapted to trip and lock by gravity with said catch, and an arrangement of means whereby said latch may be released from said catch and wedged against said lug. 50

In testimony whereof I affix my signature in the presence of two subscribing witnesses at Cleveland, Ohio; this 8th day of September, 1916. 55

GEORGE W. DONLEY.
